Primary Examiner — Nicole C Shiflet*Assistant Examiner* — Danielle Nichole Bowly(74) *Attorney, Agent, or Firm* — Peterson IP; Brett Peterson(57) **CLAIM**

I claim the ornamental design for a bolt action writing pen, as shown and described.

DESCRIPTION

FIG. 1 is a front isometric view of the bolt action writing pen.

FIG. 2 is a front view of the bolt action writing pen.

FIG. 3 is a back view of the bolt action writing pen.

FIG. 4 is a left side view of the bolt action writing pen.

FIG. 5 is a right side view of the bolt action writing pen.

FIG. 6 is a top view of the bolt action writing pen; and,

FIG. 7 is a bottom view of the bolt action writing pen.

The broken lines depict environmental structure and form no part of the claimed design.
